UNITED STATES PATENT OFFICE.

LUDWIG SCHREINER, OF BARMEN-RITTERSHAUSEN, GERMANY.

APPARATUS FOR DYEING.

SPECIFICATION forming part of Letters Patent No. 663,687, dated December 11, 1900.

Application filed August 18, 1900. Serial No. 27,334. (No model.)

To all whom it may concern:

Be it known that I, LUDWIG SCHREINER, a subject of the German Emperor, residing at Barmen - Rittershausen, Germany, have invented certain new and useful Improvements in and Connected with the Dyeing of Textile Fabrics, of which the following is a description, reference being had to the accompanying drawings, forming a part hereof.

10 The process of passing the fabrics in their full width, under tension and in alternate directions, through the dyeing fluid, as now practiced, is, in an economical sense, by far the best of the processes for dyeing fabrics, just as
15 the "jigger" (machine with reciprocating motion for dyeing fabrics in the width) is the most economically working textile-dyeing machine. The process and the machinery referred to, however, possess this disadvantage,
20 that the goods are not heavily dyed throughout, and with the small quantity of dyeing fluid employed the taking up of the dye by the fibers (especially in case of the employment of positive or direct dyeing cotton colors,
25 which are every day becoming more extensively used) becomes at once noticeable, while the adding of concentrated dyeing solution in a uniform manner during the passage of the fabrics is exceedingly difficult, the dye
30 solution being almost motionless. These disadvantages are obviated by the present invention, wherein the dyeing solution is vigorously circulated as it comes into contact with the fabrics. In this way an increased mechanical friction is obtained between the
35 goods and the dyeing solution, and thereby a more thorough dyeing of the articles throughout. The introduction of supplementary dyeing solutions (concentrated dye solutions)
40 can now be effected outside the dye-bath without the fear of any want of uniformity in the dyeing. The dyeing solution is circulated in the apparatus in alternate directions. In this way (especially when the passage of the
45 goods and the circulation of the dyeing are simultaneously reversed) the goods come into contact one after the other with the dyeing solution at both of their edges. Therefore they are dyed uniformly, and the gradual enriching
50 of the dyeing solution with dyeing material is counterbalanced by the simultaneous stronger squeezing of the goods by means

of the increasingly-heavy winding-on roller. The improved jigger for carrying out the new process is furnished, accordingly, with a 55 motor arranged outside the dye-vat, together with suitable connection-pipes between the motor and the vat and an additional pipe for the concentrated dye solution, opening into the supply-pipe. 60

If the dyeing solution circulates so that the concentrated dye solution enters the suction-pipe of the fluid-motor, it will be sufficiently mixed in the latter with the concentrated solution before entering the jigger. In order, 65 however, when the course of the circulation is reversed, to prevent any contact of the goods with the unmixed fluids, a heating-pipe is introduced into the longer pipe of the motor then acting as a pressure-pipe and the 70 dyeing solution flows in between the motor and the heating or boiling pipe.

In order, finally, to prevent any overflowing of the dyeing solution, which is vigorously moved by means of the motor and the boiling-pipe, the bottom of the jigger-vat is formed like a pipe with slots for the passage of the articles, the pipe consisting, for example, of a trough with a cover that is nearly entirely closed. 80

The drawings furnish an example of the improved jigger, Figure 1 being a front view, and Fig. 2 a perspective plan.

The bottom of the vat *a* is provided with the trough *b*, which can be closed by the cover 85 *c*, so that only two slots between trough and cover remain for the passage of the fabric. The dye-bath is forced by means of the motor *d* (a screw or a centrifugal pump or an injector or the like) through the short tube 90 *e* into the trough *b* and returns through the long tube *f* to the motor *d*. A perforated steam-tube *g* is introduced in the long tube *f*. The tube *h*, through which the concentrated dye solution is added to the dye-bath, 95 enters the long tube *f* between the motor *d* and the steam-tube *g*.

The goods run in the well-known manner from the goods-roller i over the support-roller k , are conveyed by means of guide-rollers $l l l$ through the bath in the trough b , and thereafter reach the second support-roller m and are wound up on the second goods-roller n . For the purpose of conveying the goods

through the bath under tension, the roller *i* has a brake put on it by means of the weight *o*, while the winding-on roller *n* is actuated by the support-cylinder *m*, this latter being 5 driven from the driving-shaft *p* through the medium of the double bevel-wheel *q* and the bevel-wheel *r*. On account of the varying diameter of the goods-rollers *i* *n*, resting on the support-rollers *k* *m*, the same are not 10 firmly seated, but can slide up and down in the slides *s* *t* of the stands and after the bolt *u* *v* is thrown back be taken out. The reversing of the course taken by the goods is effected also in the usual manner, the double 15 bevel-wheel *q* being put into engagement with the bevel-tooth wheel *y* of the support-roller *k* by means of the lever *x*, and the weight *o* that serves as a brake being laid over the goods-roller *n*. 20 The operation of the jigger is as follows: While the goods run from the goods-roller *i* through the bath and are wound again on the roller *n* the dye-bath in the receptacle formed by the trough *b* and the cover *c*, and being 25 thus almost entirely closed, is vigorously circulated by means of the motor *d*, and the first half of the concentrated dye solution is allowed to flow slowly through the pipe *h* and is thoroughly mixed with the bath by means 30 of the motor *d* or the boiling-pipe *g*. While the concentrated dye solution of course gradually enriches the dyeing solution with dye, the weight of the winding-on roller increases, and therefore the goods are more vigorously 35 squeezed, so that the goods are dyed uniformly. Before the "runner" ("vorläufer") has quite run down—that is to say, before the web by which the respective ends of the fabric are connected to the rollers has completely unwound 40 from the delivery-roller—the course of the goods is reversed by means of the lever *x* and

simultaneously the circulating course of the dye-bath, the second half of the concentrated dye solution being allowed to flow in, and the dye-bath now runs against the other edge of 45 the goods, and therefore effects a uniform dyeing thereof.

Having thus described my invention, the following is what I claim as new therein and desire to secure by Letters Patent: 50

1. In a machine for dyeing textile fabrics in the width; the combination of the vat, *a*, *b*, liquid-motor *d*, connecting-tubes *e*, *f*, auxiliary supply-tube *h*, and carrying and guide rollers *i*, *k*, *l*, *m*, *n*; as and for the purposes 55 herein shown and described.

2. In a machine for dyeing textile fabrics, the combination of a dye-vat, means for passing textile fabrics in the width through the vat, a liquid-motor outside the vat, connecting-pipes between the motor and vat whereby the dye solution is continuously circulated through the vat and a heating-pipe within the circulation-pipe, substantially as and for the purpose described. 60

3. In a machine for dyeing textile fabrics in the width, the combination of a dye-vat *a* having a trough-like bottom *b*, with slots in the top of said trough, means for passing goods in the width through said slots and 70 through the dye liquid in the trough, a liquid-motor outside the vat and circulation-pipes between the motor and the trough whereby the dye liquid may be continuously circulated through the trough while the goods are passed 75 through the liquid therein as explained.

In witness whereof I have hereunto set my hand in presence of two witnesses.

LUDWIG SCHREINER.
